S. GIBSON.

WIRE FENCE CLAMP.

APPLICATION FILED JULY 27, 1918.

1,321,818.

Patented Nov. 18, 1919.

UNITED STATES PATENT OFFICE.

SAMUEL GIBSON, OF WOODROW, NORTH CAROLINA.

WIRE-FENCE CLAMP.

1,321,818.

Specification of Letters Patent. Patented Nov. 18, 1919.

Application filed July 27, 1918. Serial No. 247,043.

To all whom it may concern:

Be it known that I, SAMUEL GIBSON, a citizen of the United States, residing at Woodrow, in the county of Haywood and State 5 of North Carolina, have invented a new and useful Wire-Fence Clamp, of which the following is a specification.

This invention relates to a clamp for holding woven wire fencing while being 10 stretched, one of its objects being to provide a clamp which can be placed readily in engagement with the fabric and, when once applied thereto, will not permit it to slip relative to the clamp.

15 A further object is to provide a clamp having separate means for binding it upon the fabric or fencing, said means being fastened automatically.

Another object is to provide a clamp 20 which is simple and durable in construction and can be handled readily by one person.

With the foregoing and other objects in view which will appear as the description 25 proceeds, the invention consists of certain novel details of construction and combinations of parts which will be hereinafter more fully described and pointed out in the claim, it being understood that various 30 changes may be made within the scope of the appended claim without departing from the spirit of the invention.

In the accompanying drawings the preferred form of the invention has been shown.

35 In said drawings—

Figure 1 is a view partly in side elevation and partly in section of the clamp.

Fig. 2 is an enlarged transverse section.

40 Fig. 3 is a section through the clamp and showing the holding tongs connected thereto.

Referring to the figures by characters of reference 1 designates a strip having parallel flanges extending longitudinally along one face thereof and formed in the strip at 45 desired intervals and opening between the flanges 2 are apertures 3. The face of the strip 1 opposite that from which the flanges 2 extend is formed with shallow, angular depressions 4 extending longitudinally of 50 the strip.

Secured in the flanges 2 at intervals equal

to the distances between the apertures 3 are pins 5 and on each of these pins is journaled an eccentric 6 having a lever 7 extending therefrom. A ring 8 is mounted on each eccentric and extending from each ring is a hook 9 which projects through the adjacent aperture 3. A notch 10 is formed in each lever close to its ring and pivotally connected to one of the flanges 2 and near each eccentric is a dog 11 the free end of which normally rests by gravity upon the ring.

A clamping plate 12 co-operates with the strip 1 and has longitudinal angular ribs 65 13 of the same cross sectional contour as the depressions in the strip 1. Slots 14 are formed at regular intervals in the strip or plate 12 and are so located that, when the strip 1 and plate 12 are brought together, 70 the hooks 9 will project into the slots and drop into engagement with the lower walls thereof.

Stop pins 15 are connected to one of the flanges 2 and serve to limit the backward 75 and downward movement of the hooks 9.

In applying the clamp to wire fencing, the fencing F is placed between the strip 1 and the plate 12. The dogs 11 are disengaged from the notches 10 and the levers 7 80 are swung upwardly so that the eccentrics 6 will project the hooks 9 through the fencing and into the slots 14. The levers are then swung downwardly and the eccentrics pull on the hooks so as to draw the plate 12 85 toward the strip 1 and clamp the fencing. The dogs, by dropping into the notches 10, will secure the hooks against movement to release the fencing.

As shown in Fig. 3, tongs 16 may be used 90 for pulling the clamp and thus stretching the fencing. Each of the jaws of the tongs has a stud 17 and the two studs are adapted to enter openings in the plate 12 and the strip 1 as shown at 18 in Fig. 3. Chains 19 95 or the like are connected to the other end of the tongs and by pulling them, the tongs will tightly grip and hold the clamp.

What is claimed is:—

A fencing clamp including a clamping 100 strip having spaced openings, a channelled member having spaced openings, eccentrics

mounted for rotation within the channeled member, hooks extending through the openings in the channeled member, and mounted on the eccentrics, levers extending from the eccentrics, and means within the channeled member for engaging the respective eccentrics to hold them against return movement.

In testimony that I claim the foregoing as my own, I have hereto affixed my signature 10 in the presence of two witnesses.

SAMUEL GIBSON.

Witnesses:

B. MCKERCHER,
J. P. GIBSON.
